GAS TANK STRUCTURE

Daniel A. Armstrong, Thiensville, Wis., and
Walter J. Raleigh, Roseville, Minn., assignors
to Scott-Atwater Manufacturing Company,
Minneapolis, Minn., a corporation of Minne-
sota

Application August 5, 1948, Serial No. 42,598

1 Claim. (Cl. 220—67)

1

This invention relates to a gas tank structure, and while the same might be used in many and various places, it has been particularly designed for a gas tank on an outboard motor.

It is an object of this invention to provide a simple and efficient structure of gas tank and one which can be quickly and inexpensively produced.

It is a further object of the invention to provide a gas tank structure comprising a bottom member which is quite rigid and of plate-like form, the same having a peripheral surface including a bead, a top member of inverted dish-like form made of comparatively thin material or metal and having the lower edge thereof pressed against said peripheral surface and around said bead, a sealing medium, such as cement, being disposed between said members to form a tight joint.

It is more specifically an object of the invention to provide a gas tank structure comprising a bottom plate-like member having a peripheral edge comprising a short, substantially vertical surface, a short plane surface extending outwardly from said surface and a downwardly directed bead below said second surface, together with a top member of inverted dish-like form and having its lower edge pressed against said peripheral edge and around said bead, a layer of cement, such as rubber cement, being disposed between said members to form a tight joint.

It is also an object of this invention to provide a gas tank of novel form comprising a bottom plate-like member preferably of elongated shape, said member having attaching and locating means on its lower side, a top member of inverted dish-like form having its lower edge extending about and tightly secured to said bottom member and having filling and air supply means at its top.

These and other objects and advantages of the invention will be fully set forth in the following description made in connection with the accompanying drawings in which like reference characters refer to similar parts throughout the several views and in which:

Fig. 1 is a top plan view of the tank of this invention;

Fig. 2 is a view in side elevation of said tank;

Fig. 3 is a vertical section taken on line 3—3 of Fig. 4;

Fig. 4 is a horizontal section taken on line 4—4 of Fig. 5;

Fig. 5 is a vertical section taken on line 5—5 of Fig. 4;

2

Fig. 6 is a partial vertical section taken on line 6—6 of Fig. 1;

Fig. 7 is a partial vertical section taken on line 7—7 of Fig. 4;

Fig. 8 is a partial vertical section taken on line 8—8 of Fig. 1, said sections being taken as indicated by the arrows; and

Fig. 9 is a partial vertical section showing a modification.

10 Referring to the drawings, a tank structure is shown comprising a lower or bottom member 10. Bottom member 10 is of plate-like form and is made quite rigid. While member 10 could be made in various shapes, in the embodiment of the invention illustrated it is shown as of elongated form and as substantially trapezoidal in plan at one end and as semi-circular at its other end. Member 10 has extending upwardly therefrom a cylindrical portion 10a substantially concentric with the semi-circular end thereof, which portion 10a tapers slightly upwardly. Portion 10a has projecting outwardly from its outer side a plurality of equally and circumferentially spaced strengthening ribs 10aa. Member 10 has projecting downwardly from its bottom a pair of lugs 10b having extending at opposite sides thereof strengthening ribs 10c. Lugs 10b may receive attaching studs 11 for securing said tank to its support. Member 10 has disposed substantially 15 centrally transversely at its trapezoidal end a lug 10e which projects slightly at the bottom of member 10 and has a portion projecting upwardly from the upper side thereof. A plurality of strengthening ribs 10f extend radially outward from lug 10e on the upper surface of member 10, as shown in Fig. 4. Lug 10e may also receive a stud 12 for attaching member 10 to a suitable support. Member 10 has projecting from its bottom a pair of lugs 10d which are symmetrically 20 disposed relatively to the longitudinal center line thereof. Lugs 10d serve as stops for a magneto handle. Member 10 also has projecting upwardly from its top side a plurality of equally and circumferentially spaced lugs 10g to one of which one of the ribs 10f extends. An annular lug 10h extends downwardly from the lower side of member 10 concentric with the lugs 10g. A cap 13 is provided having a flange of substantially the same diameter as lug 10h and disposed below lug 10h and connected thereto by a plurality of headed screws 14 extending therethrough and into lugs 10g. A gasket 15 is preferably disposed between said flange and lug 10h. Split spring locking washers 16 are shown as disposed between the heads of screws 14 and member 13. Member

13 is centrally bored and tapped to have secured thereto a pipe or conduit 17 through which the gasoline or other liquid passes from said tank. A boss 10i is provided at the top of member 10 concentric with lug 10h and has an opening 10j therein. Lug 10h is bored to form a shoulder with boss 10i and a screen 18 of frusto-conical form is disposed against said shoulder and held thereagainst by an annular upper flange on member 13, a gasket washer 20 preferably being disposed between said latter flange and screen 18. Screen 18 is made of minute spheres of metal, such as bronze sintered together. Member 10 has a peripheral edge which comprises a substantially vertical surface 10k of comparatively small height, an outwardly extending narrow surface 10m making a small angle with the bottom surface of member 10 and a downwardly directed substantially semi-cylindrical bead 10n. Portion 10a has adjacent its upper end an inwardly extending projection 10o which extends entirely around portion 10a, the lower part of portion 10o being substantially semi-cylindrical and forming a bead, said portion 10o having a short surface 10p extending outwardly from the inner side of member 10 at a slight angle to the bottom of member 10 to a short vertical surface 10q which extends to the top of portion 10a. A top member 21 is provided for said tank and this is made of comparatively thin material or metal which will have sufficient rigidity to adequately retain its shape against all of the ordinary incidents of use. Member 21 is of substantially the same shape and plan as member 10. As shown in Figs. 5 and 7 the lower edge of member 21 is bent around and pressed against surfaces 10k, 10m and the surface of bead 10n. A layer of sealing medium 22 is disposed between members 21 and 10, as shown in Fig. 7, and while various mediums may be used, in practice said medium has constituted a cement which does not harden, such as rubber cement. A very tight joint is thus formed between members 10 and 21. Member 21 has an annular opening therein substantially concentric with portion 10a and the inner edge portion of this opening is bent about and pressed against the surfaces 10q, 10p and the bottom surface or bead of portion 10o, as shown in Fig. 8. A layer of sealing medium 23 is disposed between said portion of member 21 and the parts 10q, 10p and 10o. This sealing medium will be of the same character as the sealing medium 22. A very tight joint is thus formed between the top of member 21 and portion 10a. The space 24 between members 10 and 21 which extends about portion 10a thus forms the liquid receiving space of the tank.

An annular member 26 formed of plate material has vertical and horizontal portions fitting along the inner and bottom sides of the bent-in portion of member 21 and member 26 will be secured to member 21 in any suitable manner, as by soldering. Soldering metal used is designated 27. Member 26 has an inwardly extending flange 26a shown as inclining slightly upwardly. Flange 26a is reenforced at equally and circumferentially spaced locations by small plates 26b welded to flange 26a. Flange 26a and plates 26b are tapped, as shown in Fig. 8, to support certain parts of the outboard motor, such as a covering cap not shown.

Member 21 has a lug 21a projecting from its top somewhat adjacent its trapezoidal end which is exteriorly threaded to receive a small nut 28 disposed at the inner side of member 21. Lug 21a is bored and tapped to receive the threaded

end of a headed screw 29 which has its head seated in a recess or bore in a swinging cover member 30. Screw 29 has a shank portion extending through a bore in member 30 and a spring tension washer 31 is disposed beneath the head of screw 29. Solder 21e is placed in the angles between nut 28 and member 21 and between nut 28 and lug 21a to form a tight seal. Member 30 is swingable about the axis of screw 29. Member 30 (see Figs. 1 and 6) is bored and tapped to have threaded therein a member 33 having a flange 33a adjacent its bottom which overlies an annular member 34 which will be made of rubber or similar material. Member 21 is provided with an opening 21b adjacent lug 21a and adjacent this opening the material of member 21 is crimped to form an annular upwardly directed ridge 21c which is engaged by washer 34. Member 33 has a terminal portion below flange 33a extending into washer 34 and washer 34 is carried by member 33. Member 33 has small rods or pins 33d projecting at opposite sides thereof and forming a handle by which member 33 may be unscrewed and member 30 can then be swung about the axis of screw 29 to uncover opening 21b. Opening 21b constitutes the filling opening for the tank. Member 33 has a rather large bore 33b extending from its bottom to adjacent the top thereof. Member 33 is also bored and tapped at its upper end to receive a headed screw 35 which will have its head provided with a knurled periphery. A washer 36 of yielding or resilient material is disposed in a shallow counterbore in the top of member 33 and adapted to be engaged by the bottom of the head of screw 35. Screw 35 extends downwardly into the bore 33b and has an annular groove formed adjacent its lower end in which is disposed a plate 37 held in position by a locking plate 38 having a top horizontal portion with an open-sided recess therein and a lower depending portion. Member 38 can be resiliently pressed laterally around the reduced portion of screw 35 and will be retained in position by its resiliency. Plate 36 is thus held against the top wall of said annular recess in screw 35. A compression coiled spring 39 surrounds screw 35 and bears at its lower end against plate 37 and at its upper end against the top of bore 33b. Member 33 is provided at its top with a plurality of small holes or passages 33c extending from bore 33b to the bottom surface of washer 36. Spring 39 acts to prevent motion of screw 35 when loosened but does not prevent entry of air through holes 33c when screw 35 is loosened.

With the described structure the tank will be secured to supports carried by the cylinder block or crankshaft case of the motor by the studs 11 and 12. The fuel, such as gasoline, will be placed in the tank by swinging member 30 to one side about the axis of screw 29. This uncovers the opening 33b so that the fuel can be poured into the tank. When the fuel has been placed in the tank, member 30 will be moved to the position shown in the drawings and member 33 can be turned by the pins 35 to press washer 34 against the rim 21c. When the motor is running and it is desired to have an air vent into the tank, the screw 35 can be rotated and moved upwardly against the tension of spring 39. Screw 35 will be loosened and air can enter the tank through the passages 33c. The gasoline will be fed to the carburetor through conduit 17, the same passing through screen 18.

In Fig. 9 a modified structure of holding the sheet 21 of the tank to the base member 10 is

shown. The base member which is designated 10' has a vertical surface 10t at its outer side which merges through a small curve into a horizontal surface 10u. When member 10 is first made it has a lug or projection 10v extending vertically from the outer end of surface 10u. The sheet 21 which is designated 21' has its lower edge bent outwardly at a right angle and said sheet is then placed against the surfaces 10t and 10u, as shown in Fig. 9, with a layer of cement 40 disposed between the inner and bottom surfaces of member 21' and the surfaces 10t and 10u. The lug or projection 10v is then bent substantially at a right angle to overlie and engage the top surface of the outwardly bent portion of member 21' and the outer vertical surface thereof. A very tight and secure joint is made between the base member 10' and the sheet 21' which forms the top portion of the gas tank. The structure shown in Fig. 9 has been used with a base member made of zinc. The base member is commonly made of aluminum. At present aluminum is not sufficiently bendable to use in the structure shown in Fig. 9 but a bendable aluminum may be perfected.

From the above description it will be seen that we have provided a comparatively simple and highly efficient structure of gas tank. In the described construction the necessity of welding parts of the tank together is eliminated. The folding over of the edge portion of member 21 onto the peripheral portion of member 10 with the use of the described cement gives a very tight and durable joint. The member 10 gives good rigidity to the tank and permits the use of lighter material for the member 21. The supporting portion 26 is easily and nicely supported on the tank. The structure has been amply demonstrated in actual practice, found to be very successful and efficient and is being commercially made.

It will of course be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claim.

What is claimed is:

A gas tank for an outboard motor having in combination, a rigid bottom member of plate-like form having horizontal upper and lower surfaces and having an upstanding solid rib

extending thereabout, said rib having a vertical outer surface, said member having a substantially horizontal surface extending outwardly from the bottom of said vertical surface and making substantially a right angle therewith, said member having a solid bead below said vertical surface substantially semi-circular in cross section and having its outer side extending to the outer end of said horizontal surface, a top member of inverted dish-like form made of flexible sheet material of much less thickness than said bottom member, the same having a portion bent closely adjacent and parallel to said vertical surface, closely adjacent and parallel to said horizontal surface and extending around said bead closely adjacent and parallel thereto and to said lower surface of said bottom member and a layer of nonhardening rubber cement disposed between and adhering to said top member and said vertical and horizontal surfaces and said bead, said top member being thus connected to said bottom member by said top member being so disposed.

DANIEL A. ARMSTRONG.
